UNITED STATES PATENT OFFICE.

ALEXANDER MCLEAN NICOLSON, OF TARRYTOWN, NEW YORK, ASSIGNOR TO WESTERN ELECTRIC COMPANY, OF NEW YORK, N. Y., A CORPORATION OF ILLINOIS.

FILAMENT FOR AUDIONS.

1,137,275.

Specification of Letters Patent. Patented Apr. 27, 1915.

Application filed June 6, 1914. Serial No. 843,504.

To all whom it may concern:

Be it known that I, ALEXANDER MCLEAN NICOLSON, a subject of the King of Great Britain, residing at Tarrytown, in the county of Westchester and State of New York, have invented certain new and useful Improvements in Filaments for Audions, of which the following is a full, clear, concise, and exact description.

10 This invention relates to filaments suitable for audions, and its objects are to provide a filament having great durability and elasticity, having the maximum surface area for the amount of material, and which will require the least amount of current for maintaining it in a state of incandescence.

With the above named objects in view the invention consists in a thin ribbon of platinum or other suitable metal in twisted form. In practice a ribbon having a width of three-tenths of a millimeter and a thickness of five-one-hundredths of a millimeter has been found to be highly efficient. Such a twisted ribbon filament is elastic. Its 25 spiral groove provides a good surface for holding the active coating, such as an oxid coating, given such filaments. The twisting operation tends to shorten the length of the flat ribbon material. Hence, to obtain a given length of twisted filament, a greater length of flat material is required. Furthermore, contiguous surfaces of the filament are brought closer together and there is less free heat radiation because of the mutual absorption of rays by the contiguous surfaces. Thus, a large surface area having a low heat radiation is provided, and hence a minimum amount of current is required for maintaining the filament in a state of incandescence.

In the accompanying drawings, Figure 1 shows, on an enlarged scale, the ribbon prior to its being twisted into shape; Fig. 2 shows, on an enlarged scale, the filament in its twisted form; and Fig. 3 is a perspective view of an audion provided with the filament of this invention.

Like letters of reference refer to like parts in the several figures of the drawing.

In the said drawings, 1 is a narrow, thin ribbon of metal, suitable for use in making the filament. Said ribbon is twisted in any suitable manner to form the filament 2. Said filament has a continuous groove 3, which as hereinbefore stated provides a good surface for holding an oxid coating and by reason of the mutual radiation of heat between the adjacent surfaces of the groove tends to hold its heat. It is also obvious that the twisted filament of this invention has a relatively large active area.

What is claimed is:

1. An audion filament consisting of a twisted metallic ribbon having an oxid coating. 65

2. An audion filament consisting of a twisted platinum ribbon having an oxid coating.

3. In an audion, a metallic filament provided with a spiral groove, and an electron-emitting coating upon the grooved portion of the filament. 70

In witness whereof, I hereunto subscribe my name this 3 day of June A. D., 1914.

ALEXANDER MCLEAN NICOLSON.
